[57] CLAIM

The ornamental design for a Phillips screw head for stripped screws, as shown and described.

DESCRIPTION

FIG. 1 is a perspective view of a Phillips screw head for stripped screws showing my new design;

FIG. 2 is a front elevational view, which is the same as the back and side elevational views;

FIG. 3 is a bottom plan view taken along lines 3—3 of FIG. 2;

FIG. 4 is a top plan view taken along lines 4—4 of FIG. 2;

FIG. 5 is a broken away sectional view taken along lines

5—5 of FIG. 3; and,

FIG. 6 is an elevational view taken from between a front and side elevational view.
